UNITED STATES PATENT OFFICE

172,713

TRAILER

Owen J. Gray, Jr., San Angelo, Tex.

Application April 1, 1954, Serial No. 29,805

Term of patent 3½ years

(Cl. D14—3)

To all whom it may concern:

Be it known that Owen J. Gray, Jr., a citizen of the United States, residing at San Angelo, in the county of Tom Green and State of Texas, have invented a new, original, and ornamental Design for a Trailer, of which the following is a specification, reference being had to the accompanying drawing, forming part thereof.

In the drawings:

I claim:

The ornamental design for a trailer, substantially as shown.
